(57) **CLAIM**

The ornamental design for a 90 degree nozzle for a drain hose, as shown and described.

DESCRIPTION

FIG. 1 is a front perspective of a 90 degree nozzle for a drain hose embodying my new design;

FIG. 2 is a rear perspective thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is left side elevational view thereof.
